E. R. CARLSON

PLIERS

Filed May 17, 1924

UNITED STATES PATENT OFFICE.

ELMER R. CARLSON, OF GALVA, ILLINOIS.

PLIERS.

Application filed May 17, 1924. Serial No. 713,988.

To all whom it may concern:

Be it known that I, ELMER R. CARLSON, a citizen of United States, residing at Galva, in the county of Henry and State 5 of Illinois, have invented certain new and useful Improvements in Pliers, of which the following is a specification, reference being had therein to the accompanying drawing.

The present invention relates to pliers, 10 and aims to provide a novel and improved implement of that kind including effective means between the handles and jaws for moving the jaws toward one another with maximum power when gripping the handles 15 in the hand.

Another object is the provision of such a tool which combines therein a bolt and nut wrench, a pipe wrench, a wire cutter, a hand vise, and a slip joint adjustment for 20 the jaws.

With the foregoing and other objects in view, which will be apparent as the description proceeds, the invention resides in the construction and arrangement of parts, as 25 hereinafter described and claimed, it being understood that changes can be made within the scope of what is claimed, without departing from the spirit of the invention.

Figure 1 is a side elevation of the pliers showing the jaws adjusted in close relation. 30

Fig. 2 is a side elevation of the tool showing the adjustment with the jaws spaced apart, and also showing the jaws swung away from one another in dotted lines.

Fig. 3 is a top view of the tool with the parts as seen in Fig. 1.

Fig. 4 is a cross section on the line 4—4 of Fig. 1.

Fig. 5 is a fragmentary elevation of one 40 lever, showing the pivot bolt in cross section.

Fig. 6 is a similar view showing the other lever in dotted lines in position as when changing the pivot bolt from one position 45 to another.

The pliers comprise the levers 10 and 11 crossing one another and having the broadened portions 12 and 13, respectively, at the point of crossing bearing against one another side by side. Said levers have the respective complementary jaws 14 and 15 beyond the portions 12 and 13. The confronting faces of the jaws have the flat pincer portions 16 at the ends of the jaws, the toothed

or notched pipe wrench portions 17 between 55 the ends of the jaws, and the wire cutters 18' and 18, respectively, at the bases of the jaws, whereby the pliers can be used as pincers, a pipe or rod wrench, and a wire cutter, as will be apparent.

The crossing portions 12 and 13 of the levers are pivoted together adjustably by a pivot bolt 19 which extends through said portions transversely, and which has a head 20 at one end and a nut 21 threaded thereon at the other terminal. The bolt or pivot member 19 has flat sides, and the portion 13 of the lever 11 has a non-circular opening 22 receiving the bolt 19, whereby said bolt 70 and lever cannot turn relatively to one another. This prevents the bolt from turning in the opening 22. The portion 12 of the lever 10 has transversely spaced circular openings 23 and 24 connected by a slot 25 which is of a width slightly less than the 75 diameter of said openings, and the bolt 19 can be disposed in either of said openings for adjusting the levers and jaws transversely relatively to one another to either of the positions shown in Figs. 1 and 2. In 80 the ordinary operative positions of the levers 10 and 11, the flat sides of the bolt 19 are disposed at an angle with the slot 25, thereby maintaining the levers in their relative pivotal adjustment, but when the levers 85 are turned to a position substantially at right angles with one another, as seen in dotted lines in Fig. 6, the bolt 19 can then pass through the slot 25 for shifting the bolt 90 from one opening of the portion 12 to the other. In this way, the pivotal adjustment of the levers can be changed when the levers 95 are moved to the position as seen in Fig. 6, and when the levers are swung toward one another to operative position and the bolt 19 is turned in either opening 23 or 24, the bolt is retained in the corresponding opening, to maintain the pivotal adjustment. This adjustment per se is well known, but 100 is taken advantage of in the present tool.

The lever 11 has a handle 26, the lever 11 being longer than the lever 10, and a handle 27 is pivoted, as at 28, to the short lever 10. The handles 26 and 27 extend from those arms of the levers 11 and 10 opposite to the jaws. The lever 27 has a lateral 105 extension 29 projecting from the pivot 28 toward the handle 26, whereby the handle

27 is in the form of a bell crank lever, the long arm of which provides the handle proper. The short arm of the bell crank lever or handle 27 is connected by a link 30 with the jaw 15 or outer arm of the lever 11, said link 30 extending obliquely across the lever 10 between the pivot bolt 19 and pivot 28. The link 30 is connected to the portion or arm 29 by the pivot 31, and the link 30 is connected to the jaw 15 by the rivet 32. The rivets constituting the pivots 28 and 31 are countersunk, as seen in Fig. 4, so as not to interfere with the link 30 and lever 11, respectively. The head 20 of the bolt 19 is flattened off at one side to accommodate the link 30 when the jaws are brought together, as seen in Fig. 1. The inner side of the lever 11 is also bevelled, as at 34, so that the portion 29 will not catch against the lever 11 when swinging the handles toward one another.

By the provision of the handle 27 pivoted to the lever 10 and the link connection between the handle 27 and lever 11, a powerful action of the jaws is provided when the handles 26 and 27 are gripped in the hand and forced toward one another. Thus, the handle 27 swings toward the handle 26 relatively to the lever 10, and applying a thrust to the link 30. When the jaws grip the object between them, so as to limit the swinging movement of the levers 10 and 11 toward one another, there is a tendency for the lever or handle 27 to swing toward the handle 26 about the pivot 31, thereby pulling on the pivot 28 in a direction along an arc around the pivot 31, thereby applying considerable power to the levers 10 and 11 for moving the jaws toward one another. Because of the link connection between the levers 10 and 27, the lever or handle 27 has a swinging movement relatively to the lever 10, so that the lever or handle 27 has a greater swinging motion relatively to the lever 11 than does the lever 10 so as to obtain a more powerful purchase.

When the lever 10 is swung to a position substantially at right angles with the lever 11, the pivot bolt 19 is turned so that it can pass through the slot 25 from the opening 23 into the opening 24, or vice versa, thereby positioning the jaws either close together or spaced apart, as seen in Figs. 1 and 2, respectively. This slip joint connection of the levers 10 and 11 permits the levers 10 and 11 to be adjusted transversely relatively to one another, and the link connection between the lever 11 and handle 27 permits of such adjustment without interfering with the lever action when the handles are swung toward one another.

Having thus described the invention, what is claimed as new is:—

1. Pliers comprising crossing levers having a pivot joint at their point of crossing

and cooperable jaws at one end, a handle pivoted to one of said levers, the other lever having a handle cooperable with the first-named handle to be grasped in the hand for moving said handles toward one another, 70 said handles being at those extremities of the levers opposite to the jaws, and a link pivoted to the first-named handle and second-named lever with said link crossing, between its pivots, the first-named lever. 75

2. Pliers comprising levers crossing one another and having a pivot joint at the point of crossing, each lever having an arm provided with a jaw and said jaws cooperating, a handle pivoted to one lever, the other lever having a handle cooperable with the first-named handle to be grasped in the hand for moving said handles toward one another, said handles being at those terminals 80 of the levers opposite to said jaws, the first-named handle having a portion extending at an angle toward the second-named lever, and a link pivoted at one end to said portion and at its other end to the second-named lever adjacent to the jaw of said lever. 90

3. Pliers comprising levers crossing one another and having a pivot joint at the point of crossing, each lever having an arm provided with a jaw and said jaws cooperating, a handle pivoted to one lever, the other lever having a handle cooperable with the first-named handle to be grasped in the hand for moving said handles toward one another, said handles being at those terminals of the levers opposite to said jaws, the first-named handle having a portion extending at an angle toward the second-named lever, and a link pivoted at one end to said portion and at its other end to the second-named lever adjacent to the jaw of said lever, said link 95 crossing, between its pivots, the first-named lever and being arranged obliquely relatively to said first-named lever. 100

4. Pliers comprising levers crossing one another and having a pivot joint at the point of crossing, said levers having cooperable jaws at one end, a handle pivoted to one lever, the other lever having a handle cooperable with the first-named handle to be grasped in the hand for moving the handles toward one another, and a link pivoted at one end to the first-named handle and at its other end to the second-named lever adjacent to the jaw of said lever and arranged to receive a compressive thrust when the handles are moved toward one another so as to force the jaws toward one another. 115

5. Pliers comprising levers crossing one another and having a pivot joint at their point of crossing, said levers having cooperable jaws at one end, a bell crank lever pivoted at its elbow to one of said levers, the long arm of said bell crank lever providing a handle, the other of said crossing levers having a handle cooperable with the afore- 125 130

said handle to be grasped in the hand for moving said handles toward one another, the short arm of the bell crank lever projecting toward the secondnamed of the crossing 5 levers, and a link pivoted at one end to said short arm and at its other end to the secondnamed of the crossing levers adjacent to

the jaw thereof, said link crossing, between the pivots thereof, the firstnamed of the crossing levers and being arranged oblique- 10 ly thereof.

In testimony whereof I hereunto affix my signature.

ELMER R. CARLSON.
